METALLOGRAPHIC POLISHING MACHINE

John P. Buckley, Washington, D. C.

Application May 15, 1931, Serial No. 537,690

10 Claims. (Cl. 51—124)

My invention relates broadly to grinding and polishing machines and more particularly to a simplified construction of grinding and polishing machine in which specimens may be formed and polished with a high degree of precision.

One of the objects of my invention is to provide a simplified construction of grinding and polishing machine wherein a centralized driving apparatus operates to perform a multiplicity of functions in the grinding and polishing of selected specimens.

Another object of my invention is to provide a simplified construction of grinding and polishing machine wherein a multiplicity of specimen carriers may be individually rotatably driven for subjecting specimens to an abrading action with respect to a rotatably driven abrading disc, the specimen carriers being automatically and periodically shifted laterally of the abrading disc for effecting a grinding and polishing operation.

Still another object of my invention is to provide a construction of metallographic polishing and grinding machine having a central vertically extending rotatably driven shaft adapted to drive an abrading disc and having means driven by said shaft for imparting rotary motion to a multiplicity of specimen carriers disposed above the disc with separate means actuated by said shaft for subjecting said specimen holders for movement laterally of the abrading disc in recurring cycles.

Other and further objects of my invention reside in a simplified construction of metallographic grinding and polishing machine as set forth more fully in the specification hereinafter following by reference to the accompanying drawings, in which:

Figure 1 is a plan view of one form of polishing machine constructed in accordance with my invention; Fig. 2 is a side elevation of a machine illustrated in Fig. 1 partially broken away to illustrate the abrading disc and arrangement of specimen holders which are driven with respect thereto; Fig. 3 is an enlarged fragmentary view showing the transmission mechanism for imparting rotary motion to each of the specimen holders; Fig. 4 is a side elevation showing the mounting of one of the specimen drivers; Fig. 5 is a plan view of one of the specimen holders shown in Fig. 4; Fig. 6 is an elevational view of the specimen holder shown in Fig. 5; Fig. 7 is a cross-sectional view of the shaft which operates the specimen driver taken on line 7—7 of Fig. 4; Fig. 8 is a plan view of the washer device which is used as a key for locking the specimen driving shaft

with respect to the driving head for each specimen holder; Fig. 9 is a plan view representing the location of the specimen holders with respect to the eccentric driving action of the abrading disc; Fig. 10 illustrates a modified method of driving the abrading disc; Fig. 11 is a plan view of the drive means illustrated in Fig. 10; Fig. 12 is a modified arrangement of specimen driver embodying my invention; Fig. 13 shows another modified form of specimen driver constructed according to my invention; Fig. 14 is an elevational view with a number of parts shown in cross-section and illustrating a modified form of the grinding and polishing apparatus of my invention; Fig. 15 is a cross-sectional view taken on line 15—15 of Fig. 14 and showing the arrangement of shifting mechanism for the specimen holders forming part of the apparatus of my invention; and Figs. 16 and 17 show a modified form of specimen driver.

Heretofore in the art the construction of metallographic polishing and grinding machines has been relatively complicated and the manufacture thereof expensive. My invention is directed to a construction of precision type metallographic grinding and polishing machine which will permit the accurate forming and polishing of specimens of various sizes. The specimens are mounted in separate specimen holders which are arranged above an abrading disc. A central driving mechanism is arranged to impart rotary movement to the abrading disc and to rotatably drive each of the specimen holders for subjecting the specimens carried thereby to an abrading operation. In one form of my invention the abrading disc is eccentrically mounted with respect to the centers of each of the drive shafts of the several specimen holders. The specimen holders may also be mounted on eccentrics so that the simultaneous drive of both the abrading disc and the specimen holders results in a planetary movement of the specimen holders with respect to the eccentric movement of the abrading disc insuring a positive polishing and grinding action of the specimens under treatment. In another form of grinding and polishing mechanism according to my invention, the specimen holders are rotated about concentric axes while the abrading disc is given a planetary movement for effecting a grinding and polishing action with respect to the specimens carried by the specimen holders. In a further form of my invention the abrading disc is driven concentrically and each of the specimen holders concentrically driven through the same driving mechanism and in addition the driving means for the specimen holders are given a lateral periodic

movement over the surface of the abrading disc for insuring an effective polishing action.

Referring to the drawings in detail, reference character 1 designates a supporting framework 5 for a table 2 having laterally extending shelves 3 and 4 therebeneath. The lateral shelf 3 provides a mounting for a pair of pulley members 5 which serves to direct the driving cable 6 from the drive pulley 46 on motor M to the driven pulley 44 on the vertically extending shaft 42 which is journaled with respect to the table top 2. The vertically extending shaft 42 which is journaled with respect to the table top 2 in the bearing 9 is secured at its upper extremity to the abrading disc 15 indicated at 41 for driving the abrading disc 41. A pan 8 is mounted on the table 2 around the rotating disc 41 to carry away any of the grinding paste, fluid, and other foreign matter through the discharge 8'. At one side of the table 2, I 20 provide a standard shown at 7 through which the vertical shaft 13 passes. The shaft 13 carries pulley 14 on the lower end thereof and pulley 15 on the upper end thereof. The shaft 13 terminates in a flange 13' which is apertured for the passage of 25 the screw 15' which engages the pulley 15. Shaft 13 may be disengaged from the pulley 15 in order that arm 10 may be swung to one side to replace disc 41 when necessary. By providing the disconnection between shaft 13 and the pulley 15 the 30 belt 20 does not drag around the pulley when the arm is swung around. The shaft 13 is journaled for rotation and is suitably aligned with respect to the supporting standard 7 by means of the bushing 12. The standard 7 terminates in a reduced neck portion 7a over which the arm 10 is 35 mounted. The arm 10 may be secured with respect to the standard 7 by means of the set screw 11 which bears against the reduced portion 7a of the standard. The arm 10 extends laterally with 40 the abrading disc 41 and provides journals for a multiplicity of driven spindles which I have designated at 21, 22 and 23 mounted in different radial positions on auxiliary arms 16 and 17 and the central arm 10 respectively. The central arm 10 and 45 the auxiliary arms 16 and 17 are arranged 120° apart so that the rotating spindles 21, 22 and 23 are permanently located at different spacial positions about the abrading disc 41. Each of the spindles is provided with a driving pulley which I 50 have designated at 24, 25 and 26 around which the driving belt 20 passes from the driving pulley 15 in the manner shown. Each of the spindles 21, 22 and 23 carries a specimen driver shown more clearly in Fig. 4.

55 The specimen drivers each comprise downwardly depending prongs which I have designated at 22', 22'', and 22''', the prongs being forked at their extremities as designated at 34 to embrace radially extending pins 35 in the specimen holder 39. The pins 35 in the specimen holder 39 are located 120° apart and permit the specimen holder to be tightly gripped by the depending prongs for rotation during the grinding and polishing action. The specimen holder is illustrated 60 in the form of an inverted cup having a flange 37 thereon and a central recess 38 therein which receives the specimen to be subjected to polishing and grinding action. The rotatable spindles are each provided with a longitudinally extending 65 groove shown more clearly in Fig. 7 where spindle 22 is designated as having a longitudinally extending groove 27. A washer member 28 is secured to the supporting plate 29 of the prong support for the rotary specimen driver by means 70 of rivet members 30 which pass through apertures 75

30' to the washer member 28. An inwardly projecting tongue 28' is carried by the washer member 28 and engages the longitudinally extending groove 27 in the rotatable spindle so that rotary motion is imparted to the prong support upon rotation of the spindle independent of vertical adjustment of the prong support along the rotatable shaft 22. Each of the rotatable spindles is provided with a central recess 32 having a spring member 33 disposed therein. The spring member 33 is confined between the end of the plunger member 31 and the end of an adjusting screw 36. The plunger member 31 is slidably disposed within an internal bore formed in rotatable shaft 22. The plunger member rests at its lower end upon the tongue 28' of washer 28. A downward force is therefore continuously applied to each of the rotating spindles for maintaining the specimens in the specimen holders against the abrading disc. The adjusting screw 36 is screw threaded into the end of the rotating spindle above the drive pulley as shown, for example, at 25 in Fig. 4. It will be understood that the plate member 29 which carries the prongs constituting the specimen holder is free to rise vertically on the rotating shaft 22, the tongue 28' of washer 28 moving in the longitudinal groove 27 in the rotatable shaft 22 and abutting against the central plunger member 31 which is yieldably adjusted in position under the action of spring 33. This combination insures a precision adjustment for obtaining the required grinding and polishing action on the specimen which is embedded in the socket 38 in the specimen holder 39. In order to insure a more positive abrading and polishing action, I may drive the abrading disc 41 through a planetary movement shown more clearly in Figs. 10 and 11. The driving shaft extending from the pulley 44 has been shown at 42 carrying a link 43 thereon which link serves as a carrier for the vertically extending rotatable shaft 51. Shaft 51 has a gear 52 thereon which is guided by the annular rack 53 around which the vertically disposed shaft 51 is driven. The gear 52 in meshing with the rack 53 serves to impart rotary movement to the shaft 51 so that the abrading disc 41 is both rotatably driven and shifted in a planetary manner for insuring a proper abrading and polishing action upon the specimens which are mounted adjacent the abrading disc. 100

As represented in Figs. 12 and 13, the specimen drivers may be each eccentrically driven. Fig. 12 shows a specimen driver wherein the rotatable shaft 22 connects to the plate member 29 adjacent one side thereof so that rotary motion imparted to shaft 22 serves to eccentrically drive the specimen holder with respect to the abrading disc. The same vertical adjustment mechanism is provided in the construction of Fig. 12 as that heretofore described in Fig. 4.

In Fig. 13, I have shown another form of eccentrically driven specimen driver wherein the plate member 29 is supported from the rotatable shaft 22 by means of a depending member 47 which extends from a laterally extending link 48 connected to the end of rotatable shaft 22. The member 47 connects centrally of the plate 29. An eccentric driving motion is therefore imparted to the specimen holder as the shaft 22 rotates. In order to provide for the vertical adjustment of the specimen holder, a laterally extending member 49 is connected immediately above the plate member 29 and is secured to the end of the plunger member 31 which extends through the bore 105 110 115 120 125 130 135 140 145 150

in the rotary shaft 22 in the manner similar to the construction illustrated in Figs. 4 and 12.

In order to provide for the more thorough grinding and polishing of the specimens I may

5 provide an additional mechanism for imparting lateral movement to the several specimen holders with respect to the abrading disc 41. As illustrated in Figs. 14 and 15, the rotatable shaft 42 which is journaled vertically of the supporting

10 frame 1 and mounted by means of bracket 54 is provided with a cam 55 which is rotatably driven for shifting the bar 56 against the action of spring 57. Spring 57 is secured to a portion of the bracket 54 which depends from the top of the

15 supporting table 2. In the arrangement shown in Figs. 14 and 15 the pedestal member 7 at one side of the table top 2 has a rotatable sleeve member 59 extending therethrough. The rotatable shaft 13 which carries the pulleys 14 and 15 is

20 journaled within the sleeve 59. The arm 10 in the form of the invention illustrated in Figs. 14 and 15 connects to the upper extremity of sleeve 59 by means of set screw 11. The construction of the arm and the depending rotatable spindles is

25 similar to the arrangement heretofore described. The lower extremity of the sleeve 59 projects beyond the member 7 and is supported therein by the abutment of the lower face of the arm 10 with the top of the member 7. The laterally extending

30 bar 56 is secured to the sleeve 59 by means of set screw 60 and is held in engagement with one side of the cam 55. The spring 57 maintains the bar 56 against the cam 55 and as the shaft 42 rotates, and moves the cam 55, an oscillatory

35 movement is imparted to the bar 56 for imparting angular movement to the sleeve 59 for correspondingly shifting the arm 10 laterally with respect to the abrading disc 41 and having the effect of shifting the spindles across the grinding surface of the abrading disc 41. This lateral movement of the several spindles is wholly independent

40 of the rotary driving movement which is imparted to the spindles through the belt 61 which is driven from pulley 45 around the pulley 14. That is to say, from the motor M power is derived

45 for imparting rotary motion to the abrading disc 41 simultaneously rotating each of the specimen holders for periodically sweeping the specimen holders laterally across the path of rotation of

50 the abrading disc. The combined action of the rotation of the spindles with respect to the movement of the abrading disc and the lateral shifting of the specimens across the grain of the abrading disc insures a thorough polishing and grinding

55 action upon the specimens within the specimen holder. The eccentric mounting of the spindles and/or the abrading disc serves to further increase the grinding and polishing action upon the specimens carried by the specimen holders.

60 Figs. 16 and 17 show a modified form of driver wherein the holder shaft 22 has a pin 22a extending laterally therethrough with the ends of the pin projecting beyond the limits of the shaft 22 for limiting the downward movement of the plate

65 29 of the specimen driver. The plate member 29 is free to be moved vertically with respect to shaft 22 for placing a specimen holder in position above the abrading disc. The plate member 29 in the modified construction shown in Figs. 16

70 and 17 is provided with a set screw 29a passing radially through the plate member 29 and having a pin 29b thereon which extends into the path of the pin 31 providing an abutment for the lower end thereof, the pin 31 being maintained under

75 tension by means of spring 33. The specimen

driver is free to be shifted vertically by means of pin 29b abutting with the lower end of rod 31 and moving the rod vertically against the action of spring 33 within limits imposed by the groove 27 in the side of shaft 22.

80

While I have described my invention in certain of its preferred embodiments, I desire that it be understood that modifications may be made and that no limitations upon my invention are intended other than are imposed by the scope of the appended claims.

85

What I claim as new and desire to secure by Letters Patent of the United States is as follows:

1. Grinding and polishing apparatus comprising a frame structure, rotary driving mechanism carried by said frame structure, a vertically extending shaft journaled in said frame structure, a rotary abrading disc carried by the upper end of said shaft, a driving connection between said rotary driving apparatus and said shaft, a vertically extending standard erected adjacent one side of said frame structure, a sleeve extending through said standard, a rotary transmission shaft extending through said sleeve and rotated from the disc carrying shaft, an arm extending laterally of said abrading disc and connected to said sleeve, a multiplicity of rotatable spindles carried by said arm immediately above said abrading disc, means for transmitting rotary motion from said transmission shaft to said spindles, and means actuated from said disc carrying shaft for imparting motion to said sleeve and swinging said arm back and forth across said disc.

90

2. In a polishing and grinding apparatus, a frame structure, rotary driving mechanism carried by said frame structure, a shaft member journaled in said frame structure, a rotatable abrading disc carried by said shaft member, connections between said shaft member and said rotary driving mechanism, a vertically extending standard erected on said frame structure adjacent one side thereof, an arm extending laterally over said abrading disc and carried by said standard, a multiplicity of rotatable spindles depending from said arm immediately above said abrading disc, a rotary transmission mechanism extending through said standard, a driving connection between the driving shaft on said abrading disc, said rotary transmission mechanism and each of said rotatable spindles, and specimen drivers carried by each of said rotatable spindles, said specimen drivers each being vertically adjustable longitudinally of said rotatable spindles.

100

3. Grinding and polishing apparatus comprising a frame structure, rotary driving mechanism carried by said frame structure, a rotary abrading disc mounted for rotation with respect to said frame structure and connected with said rotary driving mechanism, a standard erected adjacent one side of said frame structure, an arm supported by said standard, a depending rotatable spindle carried by said arm, a specimen carrier slideable longitudinally of said spindle and held against rotation thereon, means for urging said carrier downwardly and holding a specimen in contact with said disc, means for driving said spindle from said driving mechanism, and means for reversibly moving said arm laterally across said abrading disc in timed relation to the rotation of said disc.

105

4. Grinding and polishing apparatus comprising a frame structure, rotary driving mechanism carried by said frame structure, a rotary abrading disc mounted for rotation with respect to said frame structure and connected with said rotary

110

115 120 125 130 135 140 145 150

- driving mechanism, a standard erected adjacent one side of said frame structure, an arm supported by said standard, a depending rotatable spindle carried by said arm, means for driving said spindle from said driving mechanism, a specimen holder slidably carried by said spindle and held against rotation thereon, and means to yieldably urge the specimen holder downwardly and retain a specimen carried thereby in engagement with said disc. 10
5. Grinding and polishing apparatus comprising a frame structure, rotary driving mechanism carried by said frame structure, a rotary abrading disc mounted for rotation with respect to said frame structure and connected with said rotary driving mechanism, a standard erected adjacent one side of said frame structure, an arm supported by said standard, a multiplicity of depending rotatable spindles carried by said arm, means for driving each of said spindles from said driving mechanism, means operating in timed relation to the movement of said rotary abrading disc for swinging said arm successively in one direction and then in the reverse direction, a specimen holder carried by each of said rotatable spindles, the specimen holders being slidable along said spindles and held against rotation thereon, and means carried by each of said spindles for resiliently pressing said specimen holders toward said abrading disc. 25
6. Grinding and polishing apparatus comprising a frame structure, rotary driving mechanism supported by said frame structure, a vertically disposed shaft journaled in said frame structure, an abrading disc carried by said shaft, a standard erected at one side of said frame structure and extending vertically to a position above said abrading disc, an angularly movable sleeve journaled in said standard, a rotary transmission member journaled in said sleeve, an arm projecting from the upper extremity of said sleeve to a position laterally over said abrading disc, a multiplicity of rotatable spindles journaled in said arm, means interconnecting said rotary driving mechanism with said shaft for rotatably driving said abrading disc, means interconnecting said shaft with said rotary transmission member, a connection with said rotary transmission member to each of said rotatable spindles, an arm connected to said lower end of said sleeve, and a cam member carried by said arm adapted to engage said last mentioned arm for imparting periodic angular movement to said sleeve and laterally shifting said rotatable spindles across the path of said abrading disc, and resilient means for maintaining said last mentioned arm into engagement with said cam for effecting successive angular movement of said first mentioned arm. 30
7. Grinding and polishing apparatus comprising a frame structure, rotary driving mechanism supported by said frame structure, a vertically disposed shaft journaled in said frame structure, an abrading disc carried by said shaft, a standard erected at one side of said frame structure and extending vertically to a position above said abrading disc, an angularly movable sleeve journaled in said standard, a rotary transmission member journaled in said sleeve, an arm projecting from the upper extremity of said sleeve to a position laterally over said abrading disc, a multiplicity of rotatable spindles journaled in said arm, means interconnecting said rotary driving mechanism with said shaft for rotatably driving said abrading disc, means interconnecting said shaft with said rotary transmission member, a connection with said rotary transmission member to each of said rotatable spindles, an arm connected to said lower end of said sleeve, and a cam member carried by said arm adapted to engage said last mentioned arm for imparting periodic angular movement to said sleeve and laterally shifting said rotatable spindles across the path of said abrading disc. 35
8. In a polishing and grinding machine, a rotatable abrading disc, a rotatable spindle extending towards said disc, a specimen carrier, a plurality of radially disposed pins in said specimen carrier, means connected with said spindle and having a multiplicity of vertically disposed arms extending adjacent the sides of said specimen carrier, said arms being slotted for slidably engaging said pins whereby said specimen carrier is slidable with respect to said spindle towards and away from said disc and maintained in driving relation to said spindle, and means carried by said spindle to urge the carrier towards said disc and yieldably hold a specimen in engagement with the disc. 40
9. In a polishing and grinding machine, a rotatable abrading disc, a rotatable spindle extending towards said disc and formed with an axially extending bore, a specimen carrier slidably longitudinally of said spindle and held against rotation thereon and having a stem slidably received in the bore, a spring in the bore engaging said stem, and an adjusting screw engaging said spring to place the spring under desired tension and urge said carrier towards said disc. 45
10. In a polishing and grinding machine, a rotatable disc, a standard, a core journaled through said standard, an arm extending from said core over said disc, a spindle rotatably carried by said arm and extending towards the disc, a specimen holder carried by said spindle, means to rotate the disc and spindle in timed relation to each other including a transmission shaft journaled through said core, a bar projecting laterally from said core, and a rotary cam engaging said bar to impart rocking motion to said core and swing the arm to move the specimen carrier back and forth across the disc as the disc and specimen carrier rotate. 50
